Thomas Pitsanis,

INVENTOR

By *Victor J. Evans*

ATTORNEY

UNITED STATES PATENT OFFICE.

THOMAS PITsanis, OF AMBRIDGE, PENNSYLVANIA.

FUEL ECONOMIZER.

Application filed September 10, 1921. Serial No. 499,656.

To all whom it may concern:

Be it known that I, THOMAS PITsanis, a citizen of the United States, residing at Ambridge, in the county of Beaver and State of Pennsylvania, have invented new and useful Improvements in Fuel Economizers, of which the following is a specification.

This invention relates to improvements in fuel economizers and has for an object the provision of a device which may be attached to a stove or other heating element for the purpose of decreasing the amount of fuel consumed and increasing the heat furnished, by a given amount of fuel.

To this end, the invention contemplates the provision of means which may be attached to the stove or heater as a unit, for regulating the draft, so as to control the fire and for retarding the upward passage of heat through the smoke pipe or flue, whereby, said heat instead of being wasted, may be utilized for any purpose desired.

With the above and other objects in view, the invention further includes the following novel features and details of construction, to be hereinafter more fully described, illustrated in the accompanying drawings and pointed out in the claim hereto appended.

In the drawings:—

Figure 1 is an elevation showing the top portion of a stove with the invention applied;

Figure 2 is a vertical sectional view of the same;

Figure 3 is a transverse section;

Figure 4 is a detail bottom plan view of the heat retarding member, showing the apertured disc carried thereby.

Referring to the drawings in detail, where-in like characters of reference note corresponding parts, the reference character 10 indicates the top portion of a stove or similar member, which is equipped with a smoke pipe or flue 11.

The invention which is adapted to be included as a part of the flue, comprises a casing 12, having a top 13 and bottom 13^a the top being removably secured to the casing by flange 14, the latter telescoping within the ends of the casing. Both the top and bottom are provided with an opening, from which extends a collar or thimble 15 for the purpose of securing the casing 12 within the smoke pipe. It is preferred to position the

casing a short distance above the top of the stove.

Located within the casing 12 is a partition 16 which is substantially semi-circular in cross section and is attached to the inner walls of the casing 12 so as to provide an inner passage of circular sectional shape which is open at both the top and bottom.

Located within this inner passage is a heat retarding member in the form of a central shaft or standard 17 which is hollow throughout its length. This standard is surrounded by a spiral strip 18 which extends approximately from one end of the standard to the other and has its outer edges in contacting engagement with the walls of the inner passage. The bottom of the standard 17 is surrounded by an apertured disc 19 and this disc together with the spiral strip 18 act as a baffle to retard the passage of heat through the inner casing.

The space between the wall of the inner passage and the inner wall of the casing forms a draft passage and this passage is regulated by means of a damper 20, which is mounted upon a pivot 21. This pivot extends through the casing 12 and has secured upon one end an arm 22, from each end of which extend chains 23 for convenience of manipulation. The damper is held in its adjusted position through the medium of a spring 24 which surrounds the damper pivot.

After the device has been placed in position within the flue, the damper 20 is opened so as to permit the escape of smoke and gases when the fire is first started. The damper may thereafter be partly or wholly closed so as to prevent the passage of heated gases through the smoke passage. The heated gases will then enter the inner casing through the bottom thereof. Its upward passage will be retarded due to the character of the retarding member, so that instead of passing rapidly off through the flue, the heat will radiate from the casing 12.

By the use of the invention, the cost of operation of the stove or heater is materially reduced, as a much greater amount of heat can be obtained from a given amount of fuel and at the same time the fire may be effectively regulated for the proper consumption of fuel.

The invention is susceptible of various changes in its form, proportion and novel

details of construction and the right is herein reserved to make such changes as properly fall within the scope of the appended claim.

What I claim is:

- 5 In a device of the character described, a casing adapted to be interposed in a stove pipe, a member within the casing and dividing the interior thereof into two passages

open at their ends, a tubular member mounted within one passage and open at its upper and lower ends, a spiral retaining member secured to said tubular member, and means for optionally closing and opening the other passage.

In testimony whereof I affix my signature. 15
THOMAS PITTSANIS.
